(57) **CLAIM**

The ornamental design for a handheld case, as shown and described herein.

DESCRIPTION

FIG. 1 is a top, front, left side perspective view of an embodiment of the handheld case.

FIG. 2 is a front elevation view of the handheld case.

FIG. 3 is a rear elevation view of the handheld case.

FIG. 4 is a left side elevation view of the handheld case, with the right side elevation view being a mirror image.

FIG. 5 is a top plan view of the handheld case, with the bottom plan view being a mirror image.

FIG. 6 is a top, front, right, side perspective view of the handheld case with the lid shown open.

FIG. 7 is a top, front, left side perspective view of another embodiment of the handheld case.

FIG. 8 is a front elevation view of the handheld case.

FIG. 9 is a rear elevation view of the handheld case.

FIG. 10 is a left side elevation view of the handheld case, with the right side elevation view being a mirror image.

FIG. 11 is a top plan view of the handheld case, with the bottom plan view being a mirror image; and,

FIG. 12 is a top, front, right side perspective view of the handheld case with the lid shown open.

The broken lines in the drawings depict portions of the handheld case that form NO part of the claimed design.
